UNITED STATES PATENT OFFICE.

JEAN ADRIEN MOREAU, OF PARIS, FRANCE.

SPARK-PLUG.

1,306,271.

Specification of Letters Patent. Patented June 10, 1919.

Application filed January 28, 1919. Serial No. 273,577.

To all whom it may concern:

Be it known that I, JEAN ADRIEN MOREAU, citizen of the Republic of France, and resident of 96 Boulevard Péreire, Paris, in the 5 said Republic, have invented a new and useful Improvement in Spark-Plugs, of which the following is a specification.

This invention relates to spark plugs and consists in an improved spark plug which 10 is distinguished by the following features:

1. Cooling of the central electrode and of the whole plug is automatically produced by means of a heat conducting metal body, the cooling surfaces of which have been increased 15 in the largest possible measure, while the body of insulating material, which is a heat collector has been reduced to a minimum.

2. Every joint is dispensed with owing to 20 a connection by means of a metal conical shoulder; as the plug, when put together is substantially a single piece, every danger of leakage is avoided.

3. The highest degree of cooling is produced 25 at points where the heat would reach its highest value.

4. A sufficient and well protected electrical insulation by means of mica is obtained with an economy of material, the quantity 30 of mica employed being very small.

5. The electrodes can be taken out and cleaned 35 instantaneously without using any special tools and without lessening the tightness of the joint, even after the plug has been taken apart and put together again a number of times.

6. Any expansion (such as the lengthening 40 of the electrode rod at high temperatures) is made up for by expansion (lengthening) of a metal sheath which acts as a stay between the two groups of mica washers. Therefore the homogeneity and compression of the mica remain constant.

A spark plug constructed according to the 45 present system is illustrated by Figure 1 of the annexed drawing, Fig. 2 being a longitudinal sectional view of same.

The mode of construction of the improved spark plug is as follows:

50 The plug consists of a metal body 1 made on a cutting lathe, a threaded part 1^a designed to be screwed in the cylinder, a six-sided nut 1^b and a perforated tubular part 1^c, all of these parts being of steel or 55 other metal, a spring 1^d and an independent washer 14.

Said metal body 1 is centrally bored and is provided with a seat 2 the surface of which is at an angle of 45° and with a groove 3 designed to reduce the clogging 60 and situated in the rear of the threaded part 1^a.

A central electrode rod 4 of nickel-steel is provided at its extremity with a head. A small plate of pure nickel 5 constitutes the 65 electrode points. The head presses the mica washers 6 against a tube 8 which surrounds and supports the mica tube 7.

Said tube 8 is of steel or other metal for the greater part *a b* of its length, while its 70 upper end 8^a is formed by mica washers.

A nut 9 bears by means of a washer 10 against the end of tube 8, 8^a; when tightened, this nut is given a cylindrical shape 75 in order to permit it to enter with the latter into the metal body 1 or rather into a tubular extension of same, made of fibrous material. At the same time said tube 8, 8^a is given the same diameter as the internal diameter of the metal body 1, and the conical 80 shoulder at an angle of 45° which is to bear upon seat 2 is formed thereon.

The parts thus constructed having been introduced as a whole in the metal body 1, with the conical shoulder adjusted upon its 85 seat 2, they are tightened and secured in position by means of the six-faced nut 12, placed upon the independent washer 13 which itself bears against the tube 11 of fibrous material, the latter resting upon the 90 metal body 1 and upon the washer 14 compressing spring 1^d.

The cone is previously ground upon its seat 2. The spring 1^d is guided by the tubular part 1^c of the metallic body 1. 95

When desired, spring 1^d may be dispensed with; in that case the part 1^c is made thicker. It is preferable however to use a spring as a part of the metallic body, because besides a cooling action it insures the permanent 100 tightness of the joints by compensating any expansion or contraction of the parts of the plug.

Having thus described my invention and the best means I know of carrying the same 105 into practical effect, I claim:—

1. A spark plug comprising: an electrode rod; a head at one end of this rod; a thread on the other extremity of the latter; a tube made of insulating material around the said electrode; a metal tube surrounding the said insulating tube; a conical shoulder formed 110

- on said metal tube; an insulating lining at each end of the latter; an external tubular metallic body secured to the engine's cylinder; a conical seat formed inside said body; 5 a nut pressing both the insulating tube and the internal metallic tube with its linings against the head of the electrode rod; and a second nut drawing the conical shoulder formed on the internal metallic tube against 10 the seat on the external metal body.
2. A spark plug comprising: an electrode rod; a head at one end of this rod; a thread on the other extremity of the latter; a tube made of insulating material around the said 15 electrode; a metal tube surrounding the said insulating tube; a conical shoulder formed

on said metal tube; an insulating lining at each end of the latter; an external tubular metallic body secured to the engine's cylinder; a metallic spring forming an extension 20 of said body; a conical seat formed on said body; a nut pressing both the insulating tube and the internal metallic tube with its lining against the head of the electrode rod; and a second nut drawing the conical shoul- 25 der formed on the internal metallic tube against the seat on the external metal body.

In testimony, that I claim the foregoing as my invention, I have signed my name in presence of two witnesses, this seventh day 30 of January, 1919.

JEAN ADRIEN MOREAU.
